(57) **CLAIM**

We claim the ornamental design for an inside door handle for motor vehicle, substantially as shown and described.

DESCRIPTION

FIG. 1 is a perspective view of an inside door handle for a motor vehicle showing our new design, the bottom plan view is not part of the claimed design.

FIG. 2 is a top plan view of the handle.

FIG. 3 is a side elevational view thereof.

FIG. 4 is an opposite side elevational view thereof.

FIG. 5 is an end elevational view thereof; and,

FIG. 6 is an opposite end view thereof.

The broken lines form no part of the claimed design.
